(57) **CLAIM**

The ornamental design for a solid-state drive, as shown and described.

DESCRIPTION

FIG. 1 is a front, right, top, perspective view of a solid-state drive showing my new design;

FIG. 2 is a rear, left, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the area "9" shown in FIG. 1; and,

FIG. 10 is an enlarged view of the area "10" shown in FIG. 7.

The broken lines in the figures depict portions of the solid state drive which form no part of the claimed design.

1 Claim, 10 Drawing Sheets
